UNITED STATES PATENT OFFICE.

CHAPMAN SCHANANDOAH, OF NEDROW, NEW YORK.

METHOD OF CONDENSING METALS.

Application filed April 1, 1925. Serial No. 19,902.

To all whom it may concern:

Be it known that I, CHAPMAN SCHANANDOAH, a citizen of the United States, residing at Nedrow, in the county of Onondaga and State of New York, have invented certain new and useful Improvements in Methods of Condensing Metals, of which the following is a specification.

This invention relates to the treatment of steel, iron, and other metals, by means of which the molecules of the metal may be brought into closer relation with each other, for condensing, hardening and increasing the resistance of the metal, for certain purposes.

The object of the method is to compress and condense a body of metal, by subjecting said body to great pressure, said pressure preferably being greater than that usually effected by casting, rolling or forging, as commonly practiced, and the said pressure preferably being applied to the metal from opposite directions and in the same plane simultaneously, thereby subjecting the body of metal to two like forces that preferably move towards the body at the same speed and exert substantially equal pressure against the opposite sides of the metal.

In carrying out my method, the body of the metal is preferably securely mounted in a holder of suitable size, weight, and strength, to effectually resist any lateral displacement of the metal, while the body is being acted upon by the opposing compressing mediums. The sides of the body against which the impact of the agents of the force is expended, preferably project beyond and clear of the adjacent parts of the holder, so that the full compressive force may be exerted against the body, rather than being lessened and wasted by contact with the holder.

A further object of the method is to effect the condensing of a body of metal, by means of rams or projectiles of suitable size, weight and material, that may be impelled suddenly and with great force toward the body simultaneously, as by explosives, that may be detonated in unison, whereby the rams may strike with equal force against the opposite sides of the body of metal. My method includes the use of any suitable powerful explosive, by which the rams may be projected towards the body

for effecting the desired compression. In case a higher degree of density and hardness is required for certain uses, I prefer to use explosives for effecting the compression, but for ordinary uses, powerful hydraulic force may be employed, provided that the said force is exerted simultaneously from opposite directions against the body, as explained.

Another object of the method is to compress and condense metal and other bodies for producing a finer and closer grain, whereby the metal may withstand greater resistance and have greater endurance than has heretofore been attained by any other treatment known to me.

Upon investigation, I have found that when a body of metal is placed in the usual hydraulic press, the active pressure or force being applied in one direction only, and wherein this force is supplemented by the reflective force exerted by the abutment or stationary portion of the press against which the opposite side of the body contacts, effects a considerable compressing and condensing of the molecules throughout the body, the said condensation being more marked adjacent the side from which the active force is applied, but taken as a whole, the condensation effected by this single acting force is not uniform throughout the body. According to my method, the active compressive force is applied to each side of the body preferably being equal to the one-way force heretofore exerted by hydraulic and other mediums, I find that the compression of the molecules is substantially uniform throughout the body, provided that the body is properly proportioned to the force applied. I have also found that it is possible to confine the body to be compressed in a properly constructed holder in such manner that displacement of the metal laterally or perpendicularly to the line of the compression force, is negligible. By my method, the molecules of a body of metal may be suitably condensed by a single application of the opposing compressive forces, whereas by the usual method of compressing metals, where the active force is applied only in one direction, it is often necessary to shift the body and repeat the compressive operations, by applying the active force sequentially to the several sides of the body,

which increases the number of operations and greatly adds to the duration and cost of the condensing operations.

In order that my invention may be more fully understood, reference may be had to the accompanying drawing, in which is diagrammatically shown one form of apparatus, by which the various steps of the method may be carried out, in which—

10 Figure 1 is a broken central vertical longitudinal section, taken substantially on line 1—1 of Fig. 2. Fig. 2 is an end elevation of the adjustable holder. And Fig. 3 is an end elevation of one of the trough-like guides.

In the drawing, 2 represents a solid base, which may be mounted upon any suitable foundation, as 2'. 3 represents a relatively heavy and massive part, hereinafter referred 20 to as the holder, which may be formed with a central horizontal opening 3' to receive a relatively heavy bushing 4, the latter preferably being split, as shown in Fig. 2.

Intermediate its ends the bore of the bushing is contracted, as at 4', and in this contracted bore is disposed a block or body of metal 5, to be compressed. The contracted portion 4' is preferably slightly shorter axially than the block 5, as shown in Fig. 30 1, so that the block may be acted upon by the compressing mediums, without interference by the bushing. The carrier or holder 3 is preferably fitted with a number of castors or rollers, as 3', which space the 35 holder from the base 2, and provide means for trundling the holder upon the base, for adjusting as well as for mounting or removing the holder.

The plant or apparatus shown is preferably arranged for creating the force by which the block 5 may be compressed, with similar rams or projectiles, comprising relatively long, solid and heavy cylindrical bodies of steel, of suitable grade, as 6—6' 45 which are arranged to be projected or shot toward the block 5, from opposite directions, in the line of the longitudinal axis of said block and the bushing 4, by means of any suitable explosive agent, as indicated at X 50 in Fig. 1. For this purpose, the rams are preferably disposed in similar cannon-like parts 7—7', which may be mounted upon rigid bases 8. The axes of the guns 7 preferably align with the axis of the block 5. The guns 7 are preferably reinforced by bushings 7", which are encircled by cushion or recoil spring 7". The bolts 6—6' are shown projecting beyond the muzzles of the guns, but it will be understood that the said bolts may be of any suitable length, diameter and weight. The charges of the explosive X are preferably disposed adjacent reduced portions 7" of the bushings 7", and may be detonated by any of the well-known means, which need not be

shown or described in this application. The guns 7—7' are located the same distance from the block 5, and are shown in the act of discharging the rams at the same speed, preferably by identical charges of the explosive, so that said rams may strike the opposite ends of the block 5, the same measured blows for effecting uniform compression of the molecules of the block 5, in the direction of the axis of said block (see 75 dotted lines in Fig. 1). The rams 6—6' are preferably guarded against gravitational as well as lateral variations during their flight, by means of guides or ways 9, which are preferably positioned between the guns 80 and the holder, as best seen in Fig. 1. The guides 9 are substantially Y-shaped in cross-section for providing similar angular upwardly facing troughs 9', which in case the projectiles should make contact with the 85 guides, the latter may offer the least possible frictional resistance to the compressing mediums.

By my method steel may be compressed, condensed, hardened, and rendered finer and closer in its grain, thus adapting the metal for use in connection with instruments of precision, razor blades, and other edge tools, and the steps of the method may be varied within a relatively wide range to suit different requirements without departing from the spirit of the invention.

Having thus described my invention, what I claim, is—

1. The method of compressing and condensing a body of metal, which consists of confining said body to prevent lateral displacement of the metal when the body is subjected to compressive forces, and with the opposite ends of said body exposed, then compressing the said body by the impact of similar heavy bodies impelled by the force of independent explosives that are detonated in unison, whereby the said bodies may strike measured blows of equal inertial moment.

2. The method of compressing and condensing a body of metal, which consists of confining the said body to prevent the expansion or displacement of the metal laterally relatively to the axis of said body and to expose its opposite ends, then in simultaneously striking the ends of the body powerful blows of equal force by bodies impelled by the force of independent explosives.

3. In a metal condensing apparatus, a metal holder formed to receive and engage the major part of a body of metal to be condensed and to leave the ends of the body free, a pair of explosive guns arranged in spaced relation to and on opposite sides of the holder and having their bores aligned with the body of metal, and solid heavy rams received in the gun bores and adapted upon igniting of the explosives to be projected

through the space between the guns and metal body and simultaneously against opposite ends of the body of metal thereby to condense the latter.

- 5 4. In a metal condensing apparatus, a metal holder formed to receive and engage the major part of a body of metal to be condensed and to leave the ends of the body free, a pair of explosive guns arranged in 10 spaced relation to and on opposite sides of the holder and having their bores alined with the body of metal, horizontal guides spaced from the holder and alined with the gun bores, means to movably mount the 15 holder for movement into and out of alinement with the gun bores, and solid heavy rams received in the gun bores and adapted upon igniting of the explosives to be projected through the space between the guns 20 and metal body and across the guides and

simultaneously against said opposite ends of the body of metal thereby to condense the latter.

5. In a metal condensing apparatus, a metal holder formed to receive and engage the major part of a body of metal to be condensed and to leave the ends of the body free, a pair of guns arranged in spaced relation to and on opposite sides of the holder and having their bores alined with the body of metal solid heavy rams received in the gun bores, and means to project the rams out of engagement with the guns and through the space between the guns and metal body and simultaneously against opposite ends of the body of metal thereby to condense the latter. 25 30 35

In testimony whereof I affix my signature.

CHAPMAN SCHANANDOAH.
